(57) **CLAIM**

The ornamental design for a solar power module, as shown and described.

DESCRIPTION

FIG. 1 is a perspective view of the top, front, and left side of the solar power module;

FIG. 2 is a perspective view of the bottom, rear, and left side of the solar power module.

FIG. 3 is a left side view of the solar power module;

FIG. 4 is a right side view of the solar power module;

FIG. 5 is a rear view of the solar power module;

FIG. 6 is a front view of the solar power module;

FIG. 7 is a top view of the solar power module; and,

FIG. 8 is a bottom view of the solar power module.
